UNITED STATES PATENT OFFICE

LOUIS H. BARGHAUSEN, OF PITTSBURGH, PENNSYLVANIA

ARTIFICIAL-LIMB ANKLE JOINT

Application filed June 25, 1929. Serial No. 373,565.

The invention generally relates to the art of manufacturing artificial limbs and primarily has for its object to provide a novel ankle joint structure which is simple in construction and capable of being manufactured economically and in which means is provided for cushioning the walking action in a manner eliminating lost motion and enabling a wearer to walk with ease and grace and with a feeling of safety and comfort.

In the manufacture of artificial legs, especially those of the type exemplified in the patent to Hanger, No. 1,151,520, issued August 24, 1915, it is customary to join associated foot and lower leg sections by angle joints which permit movement of the foot relatively to the lower leg section about a horizontal transverse axis so that the artificial foot may simulate as nearly as is possible the natural movements of the human foot occasioned in walking. Resilient shock absorbers are interposed between the lower limb and foot sections anteriorly and posteriorly of the joint axis to cushion the walking movements, but devices thus far produced are single unit single resistance elements and do not provide for full shock absorption or flexure resistance and are open to improvement as pointed out herein. In these constructions each time a forward or progressive step is taken the rear element absorbs the shock and yieldably resists the upward movement of the heel occasioned by contact with the ground, and this upward movement of the heel is attended by a downward movement of the toe which relieves all stored up tension or resiliency in the forward element and provides a free space or lost motion at this point which must be taken up during movement toward forward transfer of weight causing an audible slap or thud which is Troublesomely perceptible to the wearer and occasions an unsafe and uncomfortable feeling in addition to hindering the practice of natural walking.

Therefore, it is an object of this invention to provide a novel composite front element which contacts with the lower limb and foot sections at all times and is capable of imparting resistance to movement of the

said sections toward each other in advance of the rocking axis in varying degrees to eliminate lost motion and facilitate natural walking.

Another object of the invention is to provide a novel standardized ankle joint plate which is interposed between the sections at the joint and secured to one thereof in a novel manner enabling adjustment of the foot section relatively to the other section when desired, and which engages and is engaged by the resilient shock absorbing elements, facilitates assembly of the joint and provides for a practical reduction in weight of the limb.

Another object of the invention is to provide a novel means to secure the axis rod or sleeve to the lower limb and foot sections in a manner assuring security in use and greatly facilitating assembly and disassembly of the elements constituting the joint.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:

Figure 1 is a vertical section taken through the longitudinal center of the foot and transversely through the ankle joint, the parts being shown in the at rest, non-walking position.

Figure 2 is a view similar to Figure 1, the heel being shown contacting with the ground as in making a progressive or forward step.

Figure 3 is a view similar to Figures 1 and 2, the weight being transferred to the ball of the foot.

Figure 4 is a vertical cross section taken through the axis of the ankle joint.

Figures 5 and 6 are top and bottom perspective views of the joint plate.

Figure 7 is a perspective view of the axis rod or sleeve and the securing eyes.

Figure 8 is a perspective view of a foot section. The foot section is rockably secured to the lower limb section and the tube 27 thus carried thereby by a U-bolt or clip 30 the legs of which pass down through the foot section holes into the recess 25. The clip 30 and the bolts 28 are removably secured to position by the nuts 31.

Figure 9 is a detail perspective view of the front cushioning element.

In the drawings in which like numerals of reference indicate like parts in all of the figures, 1 designates the lower limb section of an artificial leg, the same being hollowed out as at 2 after the common practice, and cut off straight across at its lower extremity as at 3. The straight cut face is provided with a circular recess 4 and two holes 5 are bored through the wall forming the bottom of the recess 4 and enter the hollow portion of the limb section. The purpose for thus shaping the limb section will become evident as the description progresses.

An ankle joint plate 6 is adapted to be secured to the lower end face of the section 1. These plates are of standard construction so that they can be used on all legs of a given class and are formed of metal, preferably aluminum, and each is provided with a centering boss 7 to snugly fit the recess 4 of the associated limb section. Each plate is also cored out as at 8 to further reduce its weight and includes a forwardly and downwardly extended presser toe or instep lever 9, front and rear cushion element receiving recesses 10 and 11 respectively, a transverse ankle axis rod or tube seat 12, a central arcuate grooveway or seat 13 and eye seats 14 one disposed at each side of the grooveway 13. After proper positioning adjustment facilitated by the boss and recess equipment 7, 4, the plate 6 is secured to position by screws 15.

The foot section of the limb is generally designated 16, is cored out as at 17, and includes the usual yieldable toe equipment 18 and heel cushion 19. This section also includes the posteriorly arranged cushion element receiving socket 20 which is in the nature of a vertical bore, and a somewhat square anteriorly arranged vertical socket 21 having an arcuate vertical extension 22 toward the rear and being adapted to receive the front composite cushion element.

The foot section also includes a transverse skin lined or bushed ankle axis rod or tube receiving seat 23, two lateral eye seats 24, a bottom recess 25 and two holes or bores 26 which pass through the section between the eye seats and enter the recess 25.

In the formation of the ankle joint proper I provide an axis member preferably in the nature of a simple metal tube 27 which seats in the foot section seat 23 and in the ankle joint plate seat 12, being secured in the latter by two bolts 28 each of which carries an eye 29 to snugly but slidably receive said tube and which pass through the receiving holes in said joint plate and the lower limb section into the hollow of the lower limb

section. The foot section is rockably secured to the lower limb section and the tube 27 thus carried thereby by a U-bolt or clip 30 the legs of which pass down through the foot section holes into the recess 25. The clip 30 and the bolts 28 are removably secured to position by the nuts 31.

This manner of mounting the foot section and forming the ankle joint obviates the necessity of employing a complicated specially turned and machined axis bolt, and in addition to thus reducing the cost of manufacture of the joint, greatly facilitates the assembly and disassembly of the joint.

The rear cushion element, interposed between the foot section and the joint plate in the receiving socket 20, is in the nature of a cylindrical rubber block 32 of such length that its upper end is constantly in engagement with the joint plate regardless of the position of the foot section at any given time.

The front cushion element is preferably compositely formed of two rubber blocks joined to form a unitary structure, one portion being harder or less resilient than the other. However, it is to be understood that an element formed of a single resilient substance may be employed if desired, as well as two distinct cushioning elements arranged to accomplish the purposes pointed out. In this disclosure I have shown the front element as comprising an advance somewhat square wedge shaped main body 33 of rubber and an upstanding somewhat cylindrical extension 34 likewise of rubber but softer and more resilient than the portion 33. The main body 33 seats in the foot socket 21 with the portion 34 extending into the socket or seat portion 22.

The main body 33 of the front cushion element comes into function during a part only of the walking act but the portion 34 is in contact with the joint plate constantly.

In figure 1 of the drawings I have illustrated the normal non-walking or inactive position of the parts in which the cushioning elements 32 and 34 are in cushioning contact with the ankle joint plate, the presser toe or instep lever 9 being out of contact with the front element body 33.

The start of a progressive step in walking is indicated in Figure 2 of the drawings in which the heel is shown as supporting the main portion of the weight, before transfer onto the ball of the foot. At this time the rear element 32 is absorbing the whole of the shock or cushioning all of the step weight, however, no lost motion is permitted in the ankle joint since the front element portion 34 follows the movement and remains in contact to cushion the start of movement in further progression of the step. Thus at the point in the step where lost motion has heretofore been occasioned, causing an audible shock in the joint and a feeling of uncertain-

ty, lack of perfect control and balance and discomfiture on the part of the walker, the element portion 34 assures against lost motion and gradually takes up the shock of or cushions the movement of the parts in the transferring of the weight onto the ball of the foot until its work is gradually transferred to the main body 33 which becomes active during the final portion only of the

10 step as shown in Figure 3.

Wearing limbs equipped with the ankle joint herein disclosed it is possible for persons unfortunate enough to have to use artificial limbs to walk with greater ease, comfort and assurance, and more naturally, than has heretofore been possible.

From the foregoing description taken in connection with the accompanying drawings it is thought that the novel details of construction, the manner of use and the advantages of the invention will be readily apparent to those skilled in the art.

What I claim is:

1. In an artificial limb ankle joint, foot and limb sections movable relatively during walking, cushioning means including a composite cushioning element composed of two progressively effective resilient bodies, one being in constant contact with the limb section and adapted to impose constant relatively slight resistance to the walking action, the other being brought into contact with the limb section to cushion the final portion only of a progressive walking step, the resiliency 35 of the two bodies being so related that the resistance set up by the constantly effective body gradually increases during a progressive walking step until it substantially equals the resistance of which the other body is capable at the time said other body becomes effective.

2. In an artificial limb the combination with the lower limb section, the foot section and the ankle joint cross bolt by which the sections are secured together for relative movement in simulation of natural walking, of front and rear cushioning elements interposed between the limb and foot sections anteriorly and posteriorly of the cross bolt, 50 said front element being compositely formed of a main resilient rubber body in constant contact with the limb section and an auxiliary body brought into contact with the limb section of less resilient rubber and arranged to cushion the final portion only of a progressive walking step, said main and auxiliary rubber bodies being related in resiliency whereby the resiliency of the former will substantially equal that of the latter 55 at the time the latter becomes effective.

3. A cushioning element adapted for use in artificial limbs comprising a main wedge shaped body of resilient rubber and an auxiliary body extension of resilient rubber of 60 softer and less resistant quality.

4. In an artificial limb wherein is provided a lower limb section and a foot section, an ankle joint plate secured to one section, said one section having therein a receiving recess, said plate having a positioning boss snugly fitting within the recess to permit adjustment of the plate relatively to the sections to which it is secured, and means to secure the sections together to form an ankle joint.

5. In an artificial limb wherein is provided a lower limb section and a foot section, an ankle joint plate secured to one section, said one section having therein a receiving recess, said plate having a positioning boss snugly fitting within the recess to permit adjustment of the plate relatively to the section to which it is secured, and means secured to the lower limb section and ankle joint plate and to the foot section to secure the plate in position and the sections together to form an ankle joint.

6. In an artificial limb wherein is provided a lower limb section and a foot section, a flat ankle joint plate abutting the end of the lower limb section and having an edge contour forming a continuation of said lower limb section and a forwardly and downwardly extended cushion element engaging toe, said lower limb section having therein a receiving recess, said ankle joint plate having a positioning boss snugly fitting within the recess to permit adjustment of the plate relatively to the lower limb section, means to secure the limb sections together to form an ankle joint, and front and rear cushioning elements interposed between the plate and the foot section anteriorly and posteriorly of the ankle joint to cushion the walking action movements of the ankle joint.

7. An ankle joint plate for use in artificial limbs including lower limb and foot sections, joint forming cross bolts and resilient cushioning elements; said plate comprising a flat body adapted to be secured to a lower limb section, a centering boss to engage in a recess formed in the limb section to permit adjustment of the plate relatively to the section to which it is secured, a cross recess to partially receive a cross bolt, a forwardly and downwardly extended resilient element engaging toe, said plate also having bolt securing means, accommodating apertures and recesses extending through and partially into said boss, and resilient element receiving recesses positioned anteriorly and posteriorly of the cross bolt receiving recess.

8. In an artificial limb wherein is provided a lower limb section and a foot section and cushioning elements in the foot section, an ankle joint plate comprising a flat body adapted to be secured to the lower limb section and disposed for engaging the

- 5 cushioning elements in the foot section, a recess in the lower limb section, a centering boss projecting from the plate and snugly fitting the limb section recess to permit adjustment of the plate relatively to the section to which it is secured, said plate also having a cross recess to partially receive a cross bolt, bolt apertures and receiving recesses passing through and partially projected into the boss respectively, a cross bolt seated in the cross recess, spaced eye bolts passed through the apertures and seating in the receiving recesses and adapted to snugly but removably receive the cross bolt
- 10 15 for securing it and assisting in securing the plate to position on the limb section, and a U-bolt to secure the foot section to the cross bolt for ankle-joint movement about its axis.
- 20 9. In an artificial limb wherein is provided a lower limb section and a foot section, a flat ankle joint plate abutting the end of the lower limb section and having an edge contour forming a continuation of said lower limb section and a forwardly and downwardly extended cushion element engaging toe, said lower limb section having therein a receiving recess, said ankle joint plate having a positioning boss snugly fitting within the recess to permit adjustment of the plate relatively to the lower limb section, means to secure the limb sections together to form an ankle joint, and front and rear cushioning elements interposed between the plate and the foot section anteriorly and posteriorly of the ankle joint to cushion the walking action movements of the ankle joint, said ankle joint plate having recesses therein to form seats for the front and rear elements, the said toe being disposed to engage a portion of said front element.

LOUIS H. BARGHAUSEN.
